PANEL MOUNTING

Frank Muckler, Sappington, Mo., assignor to Southern Equipment Company, St. Louis, Mo., a corporation of Missouri

Filed Dec. 4, 1958, Ser. No. 778,118

3 Claims. (Cl. 312—257)

This invention relates generally to the panel art, and in particular, to a novel mounting for attaching a wall panel to a base stand.

Heretofore, wall paneling has been fastened to base elements in some manner that required a workman to have access to the rear of the element to fasten the units together, or else required special equipment to form the desired tight connection. The prior installations have not been entirely satisfactory, due mostly to the unhandiness of having to move a cumbersome base element to attach or detach a wall panel, and also partly to the fact that mechanical connections such as screws, clamps, etc. become worn after use with the wall panel and consequently are loose fitting.

Another difficulty with some prior back bar units is that they require special fastening means for attachment to the wall of a room. Some walls are not adaptable to have the heavy back bar units attached thereto. Also the base elements and the back bar elements are heavy, and it is desirable to be able to assemble them in the work area of a room where there is space to move around, and then move the entire unit into position.

An object of the present invention is to overcome the hereinbefore mentioned difficulties, and more specifically it is an object of this invention to provide a wall panel mounting means which will provide a secure fit between wall panel and base stand without the necessity for other fastening means.

Another object of this invention is to provide a wall panel having means thereon whereby said panel can be connected to a base element from the front, obviating the necessity for moving the base element to obtain a secure fit therebetween.

A further object is to provide mounting means in combination with a wall panel and a base stand by means of which said wall panel can be securely and conveniently connected and disconnected to said base element without using other securing means.

Still another object of the present invention is to provide a means of fastening a back bar to a base stand which allows the unit to be assembled in a work area and then moved into the space where it will be used.

Another object is to provide means of fastening a back bar to a base stand whereby the need for elaborate back bar fastening means attached to the wall of a room is eliminated.

Another object is to provide a mounting means for attaching a single wall panel to a plurality of base stands. Still another object is to provide a mounting means including a member attached to the base stand and a member attached to the wall panel, said members being interlocking when the wall panel is assembled to the base stand with the bottom edge of the wall panel resting on the top of the base stand.

These and other objects and advantages will become apparent hereinafter.

The present invention comprises a mounting means to secure a wall panel to a base stand. More specifically,

2

the invention comprises a mounting means to secure a wall panel to a base element including a first member slidably positioned in a second member to move through the second member lengthwise and be entrapped therein, 5 said wall panel and base element having mutual bearing surfaces to stabilize the wall panel adjacent the base element.

The invention further consists in the panel mounting, and in the parts and combination of parts hereinafter 10 described and claimed.

Fig. 1 is a perspective view of a back bar unit showing the installation of a wall panel onto a base element utilizing the present mounting means,

Fig. 2 is a back view of the installation of Fig. 1 showing the mounting means,

Fig. 3 is a greatly enlarged broken fragmentary side view in partial section of the mounting means of the present invention, with the end cover panel broken away to show the mounting means in greater detail, taken along 20 line 3—3 of Fig. 1,

Fig. 4 is a greatly enlarged broken fragmentary back view in partial section of the present invention,

Fig. 5 is a greatly enlarged fragmentary sectional view of the mounting means taken along line 5—5 of Fig. 2, 25 and

Fig. 6 is a greatly enlarged fragmentary sectional view of the assembled mounting means taken along line 6—6 of Fig. 4.

In Fig. 1, the present invention is shown embodied 30 on a back bar unit 10 including a wall panel 11 and a base unit 12. The novel mounting means 13 which comprises this invention includes a male support member 14 fastened to the wall panel 11, and a corresponding female support member 15 fastened to the base unit 12 35 and adapted to receive the male support member 14.

The wall panel 11 includes a front panel 16 having wrap around side walls 17 at either end and U-shaped stiffening channels 18 spaced along the back thereof. The bottom edge of the front panel 16 is bent into a 40 U-shape to provide a support section 19 and an upturned strengthening lip 20 which extends between the side walls 17 of the front panel 16 (Fig. 2) The top of the front panel 16 is bent into a similar U-shape and includes section 21 parallel to section 19 and downturned lip 22. 45 A wrap-around end cover 23 is fastened onto the end of the back bar unit 10 to give a finished effect thereto. Decorative trim 24 can be added to close the space between the end cover 23 and the front panel 16. As shown in Fig. 1, the wall panel 11 includes shelves 27 and a 50 top trim panel 28.

The base unit 12 includes a cover panel 31 having a flat portion 32 forming the top of the base unit 12 and an upturned splash wall portion 33, which with the front panel 16 of the wall panel 11 forms a continuous front 55 face for the back bar unit 10. The upturned splash portion 33 is further bent in an U-shape to form a platform section 34 with a downturned strengthening lip 35 extending the length thereof. The base unit 12 itself may be any conventional type and is illustrated by a back bar 60 unit having a top 36, sides 37, a drawered front 39, and supported by legs 40.

As hereinbefore mentioned, the mounting means 13 includes a male support member 14 and a coacting female support member 15. The male member 14 is preferably 65 a U-shaped channel formed with legs 43 and 44 spaced apart by spacing member 45 and having free margins 46 and 47 respectively. The spacing member 45 is attached to the upturned lip 20 and the downturned lip 22 of the front panel 16 by any suitable means, such as spot welding, and thus forms a complete wall panel having mounting means in the form of a male support member attached thereto.

The female support member 15 is in the form of a C-shaped channel having opposed side walls 56 and 57 (Fig. 5), spaced apart by spacing member 58, and having their outer margins 59 and 60 respectively bent inwardly to trap the male support member 14 when it is inserted therein. The spacing member 58 of the female support member 15 is attached to the base unit 12 at the downturned lip 35 of the cover panel 31 and at the back 38 of said base unit 12 by any suitable means, such as spot welding.

While the mounting means have been shown as of generally U-shape and being in the form of channels, it is contemplated that they may be of any suitable shape, in so long as there is a coacting flat surface to lock the members from relative rotative movement. If more than one pair of male and female members are used, they may even be of a circular shape, because the plurality of mounting means will keep the members from any rotative movement.

When it is desired to attach a wall panel onto a base unit using the hereinbefore described mounting means, the male elements 14 attached to the wall panel 11 are inserted into the corresponding female elements 15 attached to the base unit 12 until the support section 19 of the wall panel 11 rests against the platform section 34 of the cover panel 31 of the base section 12. The U-shaped male member 14 of the mounting means 13 is enclosed by the generally C-shaped female member 15. The side walls 43 and 44 and spacing member 45 of the male member 14 have their outer faces respectively adjacent the inner faces of the side walls 56 and 57 and the spacing member 58 of the female member 15, with the free margins 46 and 47 of the male member side walls 43 and 44 entrapped by the inwardly bent outer margins 59 and 60 of the female member side walls 56 and 57.

Thus the wall panel 11 can be attached and detached to the base unit 12 without any mechanical locking means and without the necessity for a workman to have access to the back of the unit. The interlocking channels 14 and 15 form a tight and secure mounting means and the adjacent bearing surfaces 19 and 34 provide a stop means for the wall panel, and hold it adjacent an outer margin of the top of the base stand. While in the construction shown for disclosure purposes two sets of interlocking mounting means are shown, it is to be understood that one set can be used if the back bar is small, or more than two can be used if desired. Also, one wall panel can form a back for more than one base stand, if desired.

It is therefore apparent that I have provided a novel mounting means for wall panels which fulfills all the objects and advantages sought therefor.

It is to be understood that the foregoing description and the accompanying drawings have been given only by way of illustration and example, and that changes and alterations in the present disclosure, which will be readily apparent to all skilled in the art are contemplated as within the scope of the present invention which is limited only by the claims which follow.

What is claimed is:

1. In a back bar and base stand combination including a splash wall extending above the top of the base stand, the top margin of the splash wall defined by an inturned flange portion, the back bar having an inturned bottom flange coextensive with the top flange of the splash wall and engaged therewith, the improvement which comprises an open-ended first mounting member fixed to the back of the splash wall and the base stand, said mem-

ber including a back wall, spaced apart side walls and inturned flanges at the outer margins of the side walls, and a second mounting member fixed to the back of the back bar and protruding beyond the bottom flange thereof, the second member received in the open end of the first member, longitudinally movable therethrough, and including a back wall and spaced apart side walls received adjacent the corresponding back and side walls of the first member and trapped in the first member by the in-turned flanges thereon, the members being constructed and arranged so that the back bar is positioned atop the splash wall to provide therewith a smooth continuous back wall for the back bar and base stand combination.

2. In a back bar and base stand combination including a splash wall extending above the top of the base stand, the top margin of the splash wall defined by an inturned flange portion, the back bar having an inturned bottom flange engaged with the top flange of the splash wall, the improvement which comprises an open-ended first mounting member fixed to the back of the splash wall and the base stand, said member including a back wall, spaced apart side walls and inturned flanges at the outer margins of the side walls, a second mounting member fixed to the back of the back bar and protruding beyond the bottom flange thereof, the second member received in the open end of the first member, longitudinally movable therethrough, and including a back wall, and an end cover panel positioned against the end margins of the back bar, the splash wall and the base stand to hide the mounting members from view and with the side of the base stand providing a continuous side panel for the back bar and base stand combination.

3. In a back bar and base stand combination including a splash wall extending above the top of the base stand, the bottom of the back bar defined by an inturned bottom flange with an upturned lip at the outer margin thereof, the top of the splash wall defined by an inturned flange with a downturned lip in a different plane from the plane of the lip on the back bar bottom flange, the splash wall top flange and the back bar bottom flange being in engagement, the improvement which comprises an open-ended first mounting member fixed to the lip of the splash wall and the base stand, said member including a back wall equal in thickness to the lip of the back wall bottom flange, spaced apart side walls, and inturned flanges at the outer margins of the side walls, and a second mounting member fixed to the back of the back bar and protruding beyond the bottom flange thereof, the second member received in the open end of the first member, longitudinally movable therethrough, and including a back wall and spaced apart side walls received adjacent the corresponding back and side walls of the first member in uniform sliding engagement and trapped in the first member by the inturned flanges thereon, the members being constructed and arranged so that the back bar is positioned atop the splash wall to provide therewith a smooth continuous back wall for the back bar and base stand combination.
